UNITED STATES PATENT OFFICE.

REGINALD H. WATERS, OF CUMBERLAND, MARYLAND, ASSIGNOR TO KELLY-SPRING-FIELD TIRE COMPANY, OF NEW YORK, N. Y., A CORPORATION OF NEW JERSEY.

DESIGN FOR A TREAD FOR A VEHICLE TIRE.

Application filed May 1, 1925. Serial No. 13,279. Term of patent 14 years.

To all whom it may concern:

Be it known that I, REGINALD H. WATERS, a citizen of the United States, residing at Cumberland, in the county of Allegany and State of Maryland, have invented a new, original and ornamental Design for a Tread for a Vehicle Tire, of which the following is a specification, reference being

had to the accompanying drawing, forming a part thereof.

The figure is a perspective view of a portion of a tire, showing my new design.

I claim:

The ornamental design for a tread for a vehicle tire, as shown.

REGINALD H. WATERS.
